US00D976073S

(12) **United States Design Patent** (10) Patent No.: **US D976,073 S**
(45) Date of Patent: **** Jan. 24, 2023**

(54) **HANDLE FOR SCISSORS**

(71) Applicant: **TransAtlanticSalesEurope GmbH**,
Solingen (DE)

(72) Inventor: **Torsten Kretzer**, Solingen (DE)

(73) Assignee: **TransAtlanticSalesEurope GmbH**,
Solingen (DE)

(**) Term: **15 Years**

(21) Appl. No.: **29/736,630**

(22) Filed: **Jun. 2, 2020**

Related U.S. Application Data

(62) Division of application No. 29/669,264, filed on Nov. 7, 2018, now Pat. No. Des. 924,034.

(57)

CLAIM

The ornamental design for a handle for scissors, as shown and described.

DESCRIPTION

FIG. 1 is a perspective view;
FIG. 2 is a top view;
FIG. 3 is a bottom view;
FIG. 4 is a back view;
FIG. 5 is a front view;
FIG. 6 is a right side view; and,
FIG. 7 is a left side view.

1 Claim, 2 Drawing Sheets
